UNITED STATES PATENT OFFICE.

JOHN F. KIRGAN, OF EASTON, PENNSYLVANIA, ASSIGNOR TO INGERSOLL-RAND COMPANY, OF JERSEY CITY, NEW JERSEY, A CORPORATION OF NEW JERSEY.

SURFACE CONDENSER.

Application filed March 8, 1927. Serial No. 173,673.

This invention relates to surface condensers and more particularly to that type of surface condenser in which there are provided compartments dividing the cooling 5 surface into sections of various absolute pressures for the purpose of maintaining equal depth of penetration of the steam throughout the condenser.

In the type of condenser above referred to, 10 the condensate outlets and the outlets for air and uncondensable vapors are separate since this is the more practical manner of maintaining suitable vacuums in the various compartments. In order to draw off the condensate at least two condensate outlets are 15 usually provided at suitable distances from each other. More outlets are not considered necessary or desirable since this provides more joints at which air leakage may occur. 20 It is an object of the invention to prevent the vacuum in certain of the compartments from being spoiled by the generation of steam or vapor from other compartments. Other objects and advantages of the invention 25 will be in part obvious and in part pointed out hereinafter.

In the drawing forming part of the specification and in which similar reference characters refer to similar parts,

30 Figure 1 is a longitudinal vertical section through a condenser embodying the invention,

Figure 2 is a cross section of the condenser taken along the line 2—2 of Figure 1 looking 35 in the direction of the arrows, and

Figure 3 is a side elevation of the lower part of the condenser showing the means for throttling the air outlets to produce various degrees of vacuum or absolute pressure at 40 the bottoms of the condenser compartments.

Referring to the drawings, a condenser in its preferred form comprises a shell A having a steam inlet B and a plurality of tubes C arranged preferably transverse to the path 45 of the steam entering at the inlet B. The tubes C are sealed at their ends in suitable tube sheets D and E associated with an inlet water head F and an outlet water head G respectively.

50 The space within the shell A is divided transversely by suitable tube support plates H into compartments J, K, L and O each of such compartments extends from the uppermost to the lowermost rows of tubes, and by 55 reason of the direction of the flow of cooling

water from the inlet water head F toward the outlet water head G, the compartments J, K, L and O are progressively warmer in the order given since the heat from the steam condensed is absorbed by the water as it 60 passes along the length of the tubes. The temperature condition in the various compartments result in varying specific steam condensing capacity in the various compartments, the cooler compartment being adapted 65 to condense the most steam and the compartment O the least. The tendency therefore, is for the steam to penetrate less deeply in the cooler compartments than in the warmer compartments. This tendency is neutralized 70 by drawing a greater degree of vacuum in the cooler compartment J than in the warmest compartment O, the intermediate compartments K and L being adapted to be maintained at intermediate degrees of 75 vacuum. To this end, at the bottom of the condenser there are provided air outlets P which are adapted to be connected with suitable evacuating apparatus (not shown) by means of a pipe Q. Each outlet P is associated with a pair of compartments, as for instance J and K, and L and O, and one-half of each outlet P is devoted to one compartment. For this purpose the walls of the compartments J, K, L and O formed by the 80 tube support plates H are extended by means of vertical webs R to the mouth of the air outlet P. Suitable throttling plates S are interposed between the flange of the air outlet P and the pipe Q to choke the air outlet 85 an amount to correspond with the degree of vacuum desired in the various compartments. In this instance the air outlets P are adapted to be connected to separate evacuating apparatus drawing different vacuums and therefore, both throttling plates S may be alike. 90

The opening through the plates S leading to the compartments J and L are non-restricted, as at T, while the openings into the compartments K and O are effected by means 95 of a suitable number of perforations U producing the proper pressure drop into the pipes Q. Thus, there is adapted to be produced, a varying degree of vacuum decreasing from a maximum in the compartment J 100 through the compartments K and L to a minimum in the compartment O. The steam is thus caused to penetrate to the last row of tubes C throughout the length of the condenser, and hot vapor and hot condensate are 105 110

discharged from the well V at the bottom of the shell A.

As is well known, condensate at such a temperature will "flash" into steam if the absolute pressure is reduced, and therefore, by this invention the condensate before passing to common outlets W and X is removed from the compartments of lower pressure to those of higher pressure. In this instance, 10 the condensate outlet W serves the two compartments J and K and the outlet X serves the compartments L and O for the sake of convenience in piping.

In order to remove the condensate from 15 the bottom of the compartment J to the compartment K there is provided a conduit in the form of an inverted siphon or trap Y connected at two suitable apertures Z in the well V, the siphon being of sufficient depth 20 to prevent the passage of air or vapor from one compartment to the other. Likewise, condensate is removed from the compartment L to the compartment O of higher absolute pressure through a conduit b connected at the apertures c. Due to the fact that 25 the condensate in the compartments of lower absolute pressure is cooler than the condensate in the compartments of higher absolute pressure, the cooler condensate cools the warmer condensate and therefore prevents "flashing" of the condensate into steam in 30 the warmer compartments which might be caused by fluctuations in pressure.

As is understood the compartments J, K, 35 L and O should be substantially air tight near the bottom of the condenser and to this end the plates H may be packed in grooves d in the casing by means of suitable packing e.

40 Thus by the above construction are accomplished, among others, the objects hereinbefore referred to.

I claim:

1. A surface condenser comprising a casing 45 divided into a plurality of compart-

ments adapted to be maintained at various absolute pressures, a conduit to connect certain of said compartments and adapted to convey condensate, and a condensate outlet located in a compartment of greater absolute pressure whereby condensate is passed from a compartment of relatively low absolute pressure to a compartment of higher absolute pressure. 50

2. A surface condenser comprising a casing divided into a plurality of compartments adapted to be maintained at various absolute pressures, said compartments being adapted to be connected in pairs to common air evacuating devices, conduits connecting 60 the compartments in pairs and arranged to convey condensate, and condensate outlets located in the compartments of greater absolute pressure whereby condensate is passed from compartments of relatively low absolute pressure to compartments of higher absolute pressure. 65

3. A surface condenser comprising a casing, water cooled tubes extending across said casing transverse to the direction of 70 steam flow, tube support sheets sealed at their edges in said casing, walls to provide a plurality of compartments of various steam condensing capacity, said compartments being adapted to be maintained at various absolute pressures, conduits connecting the compartments in pairs and arranged to convey condensate from the compartment of lower pressure to the compartment of 75 higher pressure, and condensate outlets located in the compartments of greater absolute pressure whereby condensate is passed from compartments of relatively low absolute pressure to compartments of higher absolute pressure to prevent flashing of condensate into steam. 80

In testimony whereof I have signed this specification.

JOHN F. KIRGAN.
